UNITED STATES PATENT OFFICE

MAURICE GENSHAW, OF MOUNT MORRIS, AND ELMER KAAKE, OF FLINT, MICHIGAN

BOTTLE CLEANING BRUSH

Application filed April 27, 1931. Serial No. 533,224.

Our present invention has reference to a brush for cleaning the interior of bottles, and our object is the provision of a collapsible brush for this purpose of a construction whereby the brush proper may be swung against the stem of a handle to permit of the insertion of the brush in the bottle, and thereafter the brush is projected or extended from the handle by the operation of a rod member which is pivotally associated with one of the brush sections and slidably on the handle so that the brush may be brought to contact with all of the parts of the interior of the bottle, and by turning the same effectively clean the bottle in any easy and expeditious manner.

To the attainment of the foregoing the invention consists in the improvement herein-after described and definitely claimed.

20 In the drawings:

Figure 1 is a side elevation of a bottle cleaning brush in accordance with this invention.

Figure 2 is a similar view but showing the brush collapsed.

Figure 3 is a sectional view approximately on the line 3—3 of Figure 1.

Figure 4 is a sectional view approximately on the line 4—4 of Figure 1.

30 Preferably and as disclosed by the drawings the handle 1 of the improvement is formed on one end of a stem 2. The stem is in the nature of a wire rod of a suitable size and strength and the sides of the rod, adjacent to the ends thereof, are flattened for a considerable distance, as indicated by the numeral 3.

40 The brush is in the nature of a frame which is made up of jointed sections and preferably all of the sections are U-shaped in cross section. For distinction the inner section of the brush is indicated by the numeral 4, the said section having both of its ends bifurcated, and one of the bifurcated ends is offset and is pivoted, as at 5, to the flattened sides 3 of the stem 2. In the U-shaped frame section 4 there is received and compressed a brush 6 which may be in the nature of a piece of felt or like material but obviously also may be 45 of bristles. The second and normally outer

section of the frame is indicated by the numeral 7 and has its end received in and pivoted at the outer end of the frame section 4. The cross sectionally U-shaped section 7 carries a brush element 8 that is clamped between the sides thereof. The outer or lower section has both of its ends bifurcated and its outer end off-set and pivoted, as at 9, to the section 7, the second end of the lower section 10 being pivoted, as at 11, to the flattened end 3 of the stem 2. The cross sectionally U-shaped section 10 carries a brush element 12. Pivoted, as at 13, to the brush or frame section 4 there is the flattened end of a rod 14. The rod, adjacent its outer or free end is rounded upon itself, as at 15, and has its end formed with an eye 16 that receives therethrough the stem 2. The rounded portion 15 provides a finger hold for the rod, and the eye 16 holds the rod 14 against one side of the stem 2. Obviously by moving the rod to the position disclosed by Figure 2 of the drawings the brush frame will be collapsed and the sections thereof will be folded against the flattened end 3 of the stem 2, the section 10 of the frame projecting therebeyond. This permits of the brush being inserted in a bottle. When arranged therein the operator places his finger in the finger hold 13 and moves the rod 14 in the direction of the handle 1. This 50 expands the brush. The brush is expanded to desired extent to permit of the sections thereof being arranged at different angles with respect to each other so that the brush can operate on the neck portion of a bottle and when the frame is in substantially rectangular position as disclosed by Figure 1 of the drawings the brush can operate upon the bottom of the bottle. Of course, the bottle is partly filled with a cleansing fluid and the brush is rotated around the interior of the bottle by the manipulation of the handle 1.

55 It is thought that the foregoing description will fully and clearly set forth the advantages of the construction and the simplicity thereof so that further detailed description will not be required. Obviously we do not wish to be restricted to the specific structure herein set forth and, therefore, hold ourselves

entitled to make such changes therefrom as fairly fall within the scope of what we claim.

Having described the invention, we claim:

- 5 1. A bottle cleaning brush including a handle having a stem, a brush carrying frame comprising jointed sections whose end members are pivoted to the stem, a rod guided along the stem and pivoted to one of the frame sections at a point spaced from the stem and movable to collapse and to expand the frame.
- 10 2. A bottle washing brush, comprising a wire handle having a stem extending therefrom, and the said stem, from its outer end having its sides flattened, a brush frame comprising jointed sections which are U-shaped in cross section and which have brush elements received and clamped therein, said frame including an upper section which has an offset end that is bifurcated and pivoted to the flattened portion of the stem and a lower end which has its outer end offset, its inner end also being pivoted to the flattened portion of the stem, and an outer frame section which is pivotally secured to the upper and lower frame sections, a rod having one end pivoted to the upper frame section at a point spaced from the stem, and having its opposite end rounded upon itself and merging into an eye that receives therethrough the stem of the handle.
- 25 30

In testimony whereof we affix our signatures.

MAURICE GENSHAW.
ELMER KAAKE.
